ATTORNEYS

UNITED STATES PATENT OFFICE.

RALPH HAYS ASHER, OF LONDON, OHIO.

AIR REGULATOR.

Application filed January 3, 1921. Serial No. 434,566.

To all whom it may concern:

Be it known that I, RALPH HAYS ASHER, a citizen of the United States, and a resident of London, in the county of Madison 5 and State of Ohio, have invented a new and useful Improvement in Air Regulators, of which the following is a full, clear, and exact description.

My invention relates to improvements in 10 air regulators, and more particularly to regulation of the air entering a carburetor, and it consists in the constructions, combinations, and arrangements herein described and claimed:

15 An object of my invention is to provide a device which will automatically regulate or control the amount of air entering the carburetor, in such a manner that the fuel which is consumed by an internal combustion engine, operated in connection with the carburetor, is considerably less than where such air regulation is not used.

20 A further object of my invention is to provide an air regulator of the type described, which is made in the form of a unit that may be inserted in the air intake pipe leading to the carburetor, without the necessity of changing or altering either the pipe or the carburetor.

25 A further object of my invention is to provide a simple device consisting of few parts which are not liable to get out of order and which can be produced in quantities at a low cost.

30 Other objects and advantages will appear in the following specification, and the novel features of the invention will be particularly pointed out in the appended claims.

35 My invention is illustrated in the accompanying drawings, forming part of this application, in which—

Fig. 1 is a side view of a carburetor and an intake pipe leading thereto, the position 40 of the air regulator being shown in dotted lines,

Fig. 2 is a plan view of the air regulator,

Fig. 3 is a sectional view through a portion 45 of the air intake pipe, the carburetor connection, and the air regulator, and

Fig. 4 is an end view of the air regulator.

In the drawings, the air intake pipe is indicated at 5, this being provided with an end portion 6 arranged to be clamped to 50 the exhaust pipe 7, as in the ordinary Ford engine, for the purpose of heating the in-

coming air. The carburetor 8 is provided with the usual pipe connection 9 adapted to receive the bent end of the intake pipe 5.

The air regulator is made in the form of 60 a unit. It consists of a short tube 10 having a lateral extending end flange 11, the width of this flange being substantially that of the thickness of the wall of the intake pipe 5, as shown in Fig. 3. The opposite end of the tube is beveled and is provided with an inclined end portion 12, which has an opening 13 therein. The top portion of the tube 10 has a recess 15 for a purpose explained hereinafter. Ears 16 extend 65 forwardly from the beveled end of the tube 10 and between these ears is the pivot pin 17 of a weighted valve 18. This valve is made preferably in the shape shown in the drawings and is provided with a flat 70 face arranged to abut the inner side of the end portion 12 so as to normally close the opening 13. The valve may be made of lead or of any suitable material.

From the foregoing description of the 80 various parts of the device, the operation thereof may be readily understood. In Figures 1 and 3 the valve is shown closed. It will be observed that there is a passage-way for air through the opening 15 and between 85 the upper surface of the valve 12 on the inner wall of the intake pipe 5. When the engine is cranked, air will enter through the opening 15 and will pass on to the carburetor, mixing with the fuel and being drawn 90 into the cylinders of the engine. As soon as the engine starts, the suction of the engine will cause the valve 12 to move away from its seat thus uncovering the opening 13. The greater the speed of the engine, the 95 farther the valve will move, thus allowing more air to enter. I have found by experiment that this air control device actually saves a considerable amount of fuel in an internal combustion engine, such as the 100 Ford engine. Thus, when an engine without my improved air regulator is throttled down to a given point, the engine will stop, whereas under the same conditions, with my air regulator, it will continue to run. 105 Again, I have found that with my air regulator, the engine will start, where it will not start under the same conditions without the air regulator. When my regulator is used the needle valve of the carburetor may 110 be turned to a point which will more nearly close off the flow of fuel than is possible

under ordinary conditions. In fact, when my regulator is used, the carburetor works better when the needle valve is turned slightly from its ordinary position to shut off the ordinary fuel flow, without decreasing the power of the engine.

As stated, the device is cheap to manufacture and consists merely of two parts, to wit, the pivoted valve and the tube. It will 10 be seen therefore that there is nothing to get out of order. The regulator is placed in the end of the intake pipe and is held therein frictionally, thus requiring no retaining devices of any kind. The intake pipe is 15 then placed in the pipe connection 9 in the ordinary manner. By actual test, the device has saved over twenty-five per cent of fuel as compared with a run under precisely the same conditions without the air regulator.

20 I claim:

1. The combination with an air intake pipe of an air regulator therefor comprising a cylindrical tube adapted to enter said air intake pipe and to be frictionally retained therein, said tube having an open end, the opposite end being beveled, an end portion closing the beveled end, said end portion being provided with an opening, and a weighted pivoted valve adapted to normally rest on the inner inclined face of said end portion and to normally close the opening in said end portion, said tube being provided with an auxiliary air opening adjacent to the upper edge of the inclined end portion.

2. The combination with an air intake pipe, of an air regulator therefor comprising a cylindrical tube adapted to enter said

air intake pipe and to be frictionally retained therein, said tube having an open 40 end, the opposite end being beveled, ears extending forwardly from the beveled end, an end portion closing the beveled end, said end portion being provided with an 45 opening, said tube being provided with an auxiliary air opening adjacent to the upper edge of the inclined end portion, and a weighted valve adapted to normally rest on the inner inclined face of said end portion and to normally close the opening in said 50 end portion, said valve having a forwardly projecting portion at the upper end thereof pivotally connected to said ears.

3. A device of the character described comprising a tube adapted to enter the air 55 intake pipe of a carburetor or the like and to be frictionally retained therein, said tube having an open end, an outwardly extending flange on said tube disposed at the mouth of said open end and arranged to 60 bear against the end wall of said air intake pipe, the opposite end of said tube being beveled, an end portion closing the beveled end of said tube, said end portion being provided with an opening therethrough, and 65 an auxiliary air opening adjacent the upper edge of the inclined end portion, and a weighted valve adapted to rest on the inner inclined face of said end portion and to normally close the opening in said end portion, said valve having a forwardly projecting portion at the upper end thereof 70 pivotally connected to ears integral with said end portion.

RALPH HAYS ASHER.
